UNITED STATES PATENT OFFICE.

WALTER C. PORTER, OF WORCESTER, MASSACHUSETTS, ASSIGNOR, BY MESNE ASSIGNMENTS,
TO KRENTLER-ARNOLD HINGE LAST COMPANY, OF DETROIT, MICHIGAN, A CORPOR-
ATION OF MICHIGAN.

DIVIDED LAST.

No. 884,757.

Specification of Letters Patent.

Patented April 14, 1908.

Application filed February 3, 1902. Serial No. 92,336.

To all whom it may concern:

Be it known that I, WALTER C. PORTER, of Worcester, in the county of Worcester and State of Massachusetts, have invented an 5 Improved Divided Last, of which the following is a specification, reference being had to the accompanying drawings, in which—

Figure 1 shows my improved last in elevation, the heel section in raised position, Fig. 10 2 is a central, sectional elevation, and Fig. 3 is a sectional plan view, on line 3—3 of Fig. 2, of my improved last.

My invention relates particularly to that 15 class of lasts known as divided lasts and it has for its object to provide a last which, as soon as it is bent, shortens in length so as to allow the removal of the last from the shoe or the insertion of the last into the shoe with the utmost ease and even to permit this 20 operation when the shoe is laced or otherwise closed.

A further object is to provide a last which shall automatically lock its two parts in their operative and inoperative positions and 25 prevent too ready movement of the parts from one position to the other, said locking means not, however, preventing the ready starting of the two parts relative to each other from either of their extreme positions; 30 the locking means being so disposed as not to put the parts under strain when in their operative or inoperative positions, but acting to resist their free movement past a point intermediate such extreme positions, and a 35 further object is to provide a last which shall be composed of the minimum number of parts, having no springs, bolts, staples, or other parts designed to keep the two portions of the last in their operative 40 positions.

Another object is to provide a last which shall be absolutely automatic in its operation as well as of extreme simplicity.

In the drawings, A indicates the fore part 45 or toe part of the last, while a indicates an angular extension at the rear end of the fore part. B indicates the heel section. Fast to the heel section and projecting forward from the heel section, is a plate b. I have shown 50 this plate in the drawings as inserted for part of its length into a slot in the heel section of a width approximately equal to the thickness of the plate and secured immovably therein

by two dowel pins. This I consider the best, because the strongest and firmest construc- 55

In the rear end of the fore part is formed a slot a', which divides the extension a into two parts. Obviously this slot might be duplicated if desired, and two or more plates 60 be used to connect the heel section to the fore part, but I have found in practice that one plate b is sufficient to accomplish the desired end and have shown one plate in the drawings as the preferred form of connection. 65 The forward end of the plate b is designed to pass into the slot a' and at its extreme forward end the plate b is engaged by a pivot pin C which passes across the slot and through an aperture in the forward end of the plate b. 70 The width of the slot a' is approximately the same as the thickness of the plate b, so that no side slatting or movement takes place, the sides of the slot supporting the sides of 75 the link b and serving to guide it in its upward and downward movements as will be hereafter explained.

The pivot pin C is designedly placed as low in the last as it is possible to do, and must be on a line with, and is preferably placed below 80 the point of connection between the plate b and the heel section B in order to accomplish the ends which I have in mind and to embody my invention.

When the heel part is connected to the 85 fore part in the way I have just described and shown in the drawings, that is to say, when the heel part is pivoted upon the fore part by the pivot pin near the bottom of the last and preferably below the point of connection between the plate b and the heel section B, the heel part will obviously swing upon that pivot as a center, and it will be found that upon bending the last, that is to say, when the heel part is swung upward on its pivot the total length of the last will be immediately shortened from the very first instant that the upward movement of the heel part begins, and the lower the position in which the pivot is placed with respect to the bottom of the last the more marked will this shortening effect be. In lasts which I am now making and which embody this feature, I find that the shortening effect is equal to two sizes at least. This feature of my invention is an important matter, since it enables 95 100 105

the last to be removed from a shoe even when laced, if desired, without strain or liability to injure the lining of the shoe and so marked is the shortening effect that my improved last can be replaced in a laced Oxford shoe without the use of a shoe-horn.

It will be seen that the knuckles formed by the two parts of the extension *a* are shallow in vertical depth and project to the rear so as to be overhung by the forepart for a considerable horizontal distance. This, taken together with the fact that the plate *b* is short from its pivot *c* to the abutting line of cleavage or the secant surface which it crosses to connect with the heel part, said pivot *c* being located approximately in a vertical plane below the long vertical wall of the forepart above the knuckle, constitutes my invention, and is of great importance and value because by reason of this construction the last must shorten at once and rapidly upon being bent, the wood as well as the hinge takes the downward leveling strains (as distinguished from the nearly vertical line of cut when the last is extended in Krentler No. 764,894), no shearing strain can come directly on the hinge itself, and the rear heel line can be much less rounded than in such a construction as that of Tyler No. 601,621 or of Arnold No. 607,978.

The last is also exceedingly simple, easy to manufacture, and the wide extent of overhanging and contacting surface when the last is in its lengthened position, makes twisting movement practically impossible.

Another and exceedingly important feature of my invention is the automatic self-locking feature, by virtue of which the two parts of the last are automatically secured and locked in their operative and inoperative positions, respectively.

It will be observed by referring to the drawings, that the extension *a* is angular. If a circle be struck from the pivot pin *C* as a center, to touch but not cross the line of the front face of the heel part *B*, it will be seen that a protuberance or angular point or portion *x* of the extension *a* is outside the circle above mentioned, and it will be obvious that the point upon the face of the rear part *B* which is touched by the circle above mentioned, since that point swings about the pivot *C* as a center, will necessarily tend to move in the line of the circle, and it will be also obvious that since the protuberance *x* upon the rear face of the extension *a* projects outside the circle the protuberance *x* will be in the path of that part of the face of the heel part *B* which was touched by the circle above mentioned, since this portion of the heel part *B* will necessarily follow the line of the circle while the protuberance projects beyond the circle. It will be observed that the protuberance *x* projects within the path of the

face of the heel part as above mentioned only to a slight degree, and it is this protuberance *x* which operates as a locking device, for as the heel section swings upward in a circular path upon the pivot *C* as a center the protuberance *x* will frictionally resist the upward movement of the heel section and tend to force the heel section away from the forepart section, straining the connecting parts and causing the material of which the last is made to yield slightly wherever the strain falls. As soon as the engaging surface of the heel section *B* passes the protuberance *x*, the natural inherent elasticity of all the parts will operate to draw the heel section and the fore-part section together to their normal closeness, and the heel section will thus be held in its elevated position until, by the exercise of considerable force, it is again thrown over the protuberance *x*, when again the natural elasticity of the parts locks the heel section *B* in its operative or lower position.

With relation to the fore-part *A* it is obviously important that the heel section should be stopped in its downward movement when it reaches its operative position, that is to say; when the bottom surfaces of the parts *B* and *A* register together, since it is important that the bottom surface of the last shall be continuous, but it is obvious that this stopping of the heel part in its downward movement might be accomplished by any ordinary stop, as, for example, a pin across the slot *a'* at some point where it would be engaged by the plate *b* at the proper moment. The lower face of the extension *a* which I have designated by the letter *y* and which, projecting in the path of the heel part *B*, serves as a stop to limit the downward movement of the heel part *B* is not therefore a feature of my invention.

The protuberance *x* upon the rear face of the extension *a* may be situated at any convenient position on the rear face of extension *a*, the only requirement being that it shall so project as to be slightly in the path of some point upon the face of the heel section *B* as it moves up or down, and obviously the shape and angles shown in the drawings are not of the essence of my invention though they show convenient and operative shapes and angles for carrying my invention into practice, so far as this automatic locking feature is concerned. The protuberance *x* as shown in the drawings and described in this specification is an integral portion of the extension *a* but the effect might be attained by a wooden or metal projection connected to the face of the extension *a* and projecting into the path of some part of the face of the heel section *B*, the principle of operation being that a point upon the face of the extension *a* shall be in the path of a point upon the face

of the heel section B and tend to obstruct its upward or downward movement when the two points are passing.

I claim:

1. A last, comprising a forepart and a heel-part, separated by a transverse cut extending diagonally upward and forward for a limited distance from the bottom of the last for giving an extended horizontal overlap to the contacting surfaces fitting each other tightly when the last is extended, and by surfaces diverging from the upper end of said cut and providing a recess below the top of the last when the latter is in extended position, in combination with a central vertical hinge-plate rigidly connected to the heel-part and pivotally connected to the forepart more than half-way from the bottom of said recess to the bottom of the last, said hinge-plate and its pivotal connection being constructed and arranged with relation to the secant surfaces of the adjacent ends of the forepart and heel-part to permit the heel-part to move upwardly and to shorten instantly at the beginning of its upward swing, and to separate said overlapping surfaces angularly from each other, swinging the upper diverging surface of the heel-part forward for closing said recess.
2. A hinged last, having its parts separated by a wide gap formed by an approximately vertical wall at the upper rear end of the forepart and an oblique wall at the upper forward end of the heel-part, said wall of the

forepart extending approximately midway to the bottom of the last, said forepart having an extension, shallow in vertical depth, projecting from the lower end of said forepart wall and having its top secant surface extending in a rearward direction to its extreme end at the bottom of the last, the entire contacting surface therewith of said heel-part extending forward at all points from the point of intersection of said extreme end with the bottom of the last, for giving a maximum horizontal overlap to said contacting surfaces, and a central vertical hinge-plate rigidly connected to the heel-part and pivoted to the forepart low down in said extension more than half way from the top of the latter to the bottom and in approximately vertical alinement with said rear vertical wall of the forepart to shorten the last rapidly and immediately when the heel-part is turned upward upon its pivot, said hinge-plate and its pivotal connection being constructed and arranged with relation to the secant surfaces of the adjacent ends of the forepart and heel-part to permit the heel-part to move upwardly and to separate said overlapping surfaces angularly from each other, swinging the upper diverging surface of the heel-part forward for closing said recess.
